CHOCOLATE RABBIT

Richard M. Palmer, Wyomissing, Pa.

Application March 9, 1955, Serial No. 34,963

Term of patent 14 years

(Cl. D82—2)

FIG. 1.

FIG. 3.

FIG. 2.

FIG. 4.

Figure 1 is a front elevational view of a chocolate rabbit in accordance with my new design.

Fig. 2 is a rear elevational view thereof.

Fig. 3 is a side elevational view, as seen by looking at Fig. 1 from the right, and

Fig. 4 is a side elevational view, as seen by looking at Fig. 2 from the right.

I claim:

The ornamental design for a chocolate rabbit, as shown.
